CLAIM

The ornamental design for a toy for animals, as shown and described.

DESCRIPTION

Toy for animals

1.1 is a perspective view of the toy for animals;

1.2 is a front view thereof;

1.3 is a front view thereof;

1.4 is a back view thereof;

1.5 is a left side view thereof;

1.6 is a right side view thereof;

1.7 is a top view thereof;

1.8 is a bottom view thereof;

1.9 is an exploded view thereof.

The broken lines illustrate portions of the toy for animals that form no part of the claimed design. The portion of the design shown in the color gray is for the purpose of illustrating portions of the article that forms part of the claimed design.

1 Claim, 9 Drawing Sheets
